UNITED STATES PATENT OFFICE.

KARL VÖLLER, OF DUSSELDORF, GERMANY.

AUTOMATICALLY-OPERATING KEY FOR SETTING THE TIMING-RINGS OF FUSES FOR SHELLS OR THE LIKE.

1,037,811.

Specification of Letters Patent.

Patented Sept. 3, 1912.

Application filed May 3, 1910. Serial No. 559,162.

To all whom it may concern:

Be it known that I, KARL VÖLLER, engineer, a subject of the German Emperor, residing at 17 Jülicherstrasse, Dusseldorf, Germany, have invented certain new and useful Improvements Relating to Automatically-Operating Keys for Setting the Timing-Rings of Fuses for Shells or the Like; and I do hereby declare the following to be a full, clear, and exact description of the invention, such as will enable others skilled in the art to which it appertains to make and use the same.

The present invention relates to operating keys for setting the timing rings of fuses for shells or the like of the kind having two relatively movable parts, which parts are set with certainty upon the desired division of a scale carried by one of the parts by the automatic engagement of a bolt with a corresponding rack.

In known constructions of this kind the arrangement of the bolt has been such that when the timing ring is being set an unintentional pressure of the finger or a shock might cause the bolt to become disengaged from the rack and thus render the setting of the timing ring inaccurate.

The present invention has for its object the provision of means for obviating this disadvantage, the bolt being so arranged that when the timing ring is being set the bolt will be prevented from moving from its locked position.

The invention will be hereinafter fully set forth and particularly pointed out in the claims.

In the accompanying drawings, Figure 1 is a longitudinal section through the key on line 1—1, Fig. 2. Fig. 2 is a plan view, with parts in section, on line 2—2, Fig. 1. Fig. 3 is a sectional view of the handle and ring. Fig. 4 is a plan view thereof.

Referring to the drawings, a ring *b* is fixed to the handle *a*, or is, preferably, made in one piece therewith. In this ring *b* is an adjustable slide *c*. This slide carries a projection *d* necessary for setting the timing ring of a fuse. The movement of the slide *c* and its projection *d* can be read on the scale *f* by a pointer *e*, so that any necessary correction in the positioning of the fuse can be made.

The ring *b* is surrounded by a second ring *g*, which latter has an inwardly projecting

flange *h* lying against the first-named ring. A third ring *i* screwed into the ring *g* connects the latter with the ring *b* in such manner that the two rings can be rotated relatively to each other, but cannot be displaced axially.

On the ring *g* is a second projection *r* necessary for setting the fuse, and this ring also has affixed thereto an annular scale *l*, while the ring *b* carries an index according to which the necessary period of combustion for the fuse may be set.

The ring *g* has on its inner periphery a series of teeth *q* which correspond exactly with the division marks of the annular scale. Intermediate teeth may also be provided which correspond with semi-divisions of the scale. With the teeth *q* engages a tooth *n* on a bolt *m* mounted to move radially in the ring *b*. The bolt *m* is subject to the pressure of a spring *o* which keeps the tooth *n* engaged with the ring *q*. When the two rings required for setting the fuse are to be relatively displaced the thumb of the hand holding the handle *a* presses against the roughened surface *p* of the bolt *m* so as to disengage the tooth *n* from the teeth *q* of ring *g*. When the two rings have been adjusted the bolt *m* is released by removing pressure from the surface *p* and the rings are again automatically locked.

The bolt *m* abuts against the periphery of the fuse (as shown in dotted lines in Fig. 1) when the latter is in position in the key. The fuse itself therefore prevents the bolt *m* from shifting toward the middle of the key and thus provides against disconnection of the adjusted parts.

I claim as my invention:

1. In an automatically operating key for setting time fuses on shells or the like, the combination of two relatively movable parts, one of which is designed to engage a movable member of the fuse, a handle carried by one of the parts, a bolt, carried by the same part, a rack, carried by the other part, and means for holding the bolt in engagement with the rack.

2. In an automatically operating key for setting time fuses on shells or the like, the combination of two relatively movable parts, one of which is designed to engage a movable member of the fuse, a handle, carried by one of the parts, a bolt, carried by the same part, a rack, carried by the other

part, with which the bolt engages, and means for normally holding the bolt in engagement with the rack, a part of the bolt extending over the handle.

5 3. In an automatically operating key for setting time fuses on shells or the like, the combination of two relatively movable parts, one of which is designed to engage a movable member of the fuse, a bolt on one of 10 the contiguous faces of one of the relatively movable parts, a rack on the other relatively movable part, and means for holding the bolt in engagement with the rack.

4. In an automatically operating key for 15 setting time fuses on shells or the like, the

combination of two relatively movable parts, one of which is designed to engage a movable member of the fuse, a handle on one of such parts, a rack on the other of said parts, such rack surrounding the part 20 having the handle, a radially movable bolt within the latter part, and means for holding the bolt in engagement with the rack.

In witness whereof I have hereunto set my hand in presence of two witnesses.

KARL VÖLLER.
